UNITED STATES PATENT OFFICE.

EUGENE C. PECK, OF CLEVELAND, OHIO, ASSIGNOR TO THE CLEVELAND TWIST DRILL COMPANY, OF CLEVELAND, OHIO, A CORPORATION OF OHIO.

CHUCK.

1,008,057.

Specification of Letters Patent.

Patented Nov. 7, 1911.

Application filed March 27, 1907. Serial No. 364,762.

To all whom it may concern:

Be it known that I, EUGENE C. PECK, a citizen of the United States, residing at Cleveland, in the county of Cuyahoga and State of Ohio, have invented a certain new and useful Improvement in Chucks, of which the following is a full, clear, and exact description.

My invention relates to drill chucks and is more particularly directed to that style of chuck which is adapted to receive and hold drill shanks having two opposite longitudinal V grooves therein.

The object of the invention is to provide a form of chuck which shall overcome those defects present in the drill chucks now known, such as liability of the jaws slipping and the hood to yield to sidewise strain and the lack of sufficient side bracing to prevent the shearing of the jaws. To achieve these results, I have embodied my invention in concrete form as described in the following specification and illustrated in the accompanying drawings in which—

25 Figure 1 is a side elevation partly broken away and in section, showing the assembled chuck. Fig. 2 is a view similar to Fig. 1 showing the chuck body. Fig. 3 is an end view of the assembled chuck. Fig. 4 is a 30 side view showing a jaw. Figs. 5 and 6 are respectively views of opposite ends of a jaw.

I provide the body A of my chuck with a threaded portion A' designed to receive a hood B having an internal thread B' and 35 an internal conical taper B². Back of the threaded portion A' on the body I provide a cylindrical bearing surface A² adapted to receive the rear end B³ of the hood which is closely fitted thereto. The forward end of 40 the body beyond the threaded portion is reduced and slotted at A³ to receive the radially reciprocative V jaws C which, in the present instance, are shown as two in number and provided with suitable retaining 45 means to prevent them from dropping through their respective slots, the means shown consisting of a rod spring C' extending through the length of the jaw and resting at each end upon a ledge A⁴ at the end 50 of the slot. The outside of the jaws is given a conical taper C² to fit the interior conical taper B² of the hood while the apex C³ of the V edge of the jaws is straight lined to fit the V groove in the shank of the drill. 55 The extreme forward end A⁵ of the chuck

body is cylindrical in curvature and concentric with the cylindrical bearing surface A² previously described as located behind the threaded portion of the body. The hood is fitted to the bearing surface A⁵ at the forward end of the body. It is further to be noted that the forward bearing A⁵ extends entirely around the tool-receiving opening and thus bridges the forward ends of the jaw slots A³ so that there is one continuous band of metal at this end of the chuck. I also prefer that small projections A⁶ be formed on this band immediately in front of the jaw slots, which additional pieces of metal not only increase the strength of the band at this point but serve as indices projecting from between the hood to indicate to the operator the alinement to observe in inserting his tool shank into the chuck in order that the grooves may coincide with the jaws of the chuck.

From the structure above described, it will be evident that, upon rotating the hood in the ordinary manner to the right, the cone of the hood will pass up on the jaws 80 and advance them with a parallel motion into the grooves in the shank of the tool. It is further to be observed that the hood, which backs the gripping jaws and receives the tremendous pressure to which the jaws 85 are subjected, tending to move them out of their true concentric position, is provided with fitted concentric bearing surfaces near its extremities, beyond each end of the gripping jaws, thus providing the most rigid 90 and secure bracing possible so that there is no means by which it could possibly give or vibrate.

It will be seen that the sidewise twist given to the jaws is resisted along their 95 sides and at each end thus preventing them from twisting or being sheared off at some point intermediate their ends. Again, it is to be noted that the sides of the jaw slots are, in my construction, closed and tied together at both ends so that although the sides of the slot receive and take up the side twist given to the jaws, nevertheless they will not split or spring, except under a pressure which would burst a cylinder so slotted. 100

The gripping jaws fit rather closely the slots in which they float and any unevenness in their movement would probably cause them to bind. It will be seen, on referring to the drawing, that I have formed a horizontal 110

opening through each jaw, which opening is adapted to receive the supporting spring but which has a bearing surface for such spring located so as to insure that the resultant thrust or tension of the spring shall be exerted along a line passing approximately through the center of the jaw. This will give an even movement of the jaw through the slot in which it floats so that there will be no binding or crowding at either end or side.

Having thus described my invention, I claim:

1. A chuck having an integral body provided with supporting bearing surfaces at its ends and being provided with slots intermediate of said bearing portions, the said chuck body being screw threaded between the rear bearing surface and the rear end of the slots, jaws mounted in said slots, said jaws being tapered upon their upper sides, a hood mounted upon the said body and having a portion of its inner surface tapered complementarily to the taper upon the jaws, the said hood having portions which bear upon the bearing surfaces upon the chuck body, the interior portion of said hood being provided with screw threads which engage with the screw threads upon the body of the chuck, substantially as described.

2. A chuck having a slotted body, jaws mounted in said slots and having resilient members adapted to travel in extensions of said slot, and a hood for actuating said jaws.

3. A chuck comprising in combination, a chuck body having jaws resiliently mounted in slots therein, said chuck body terminating at opposite ends in concentric smooth bearing surfaces, a hood mounted on said chuck body and adapted to move longitudinally on said oppositely arranged bearing surfaces to advance the said jaws toward the axis of the body.

4. A chuck having an integral body with concentric supporting surfaces, an axial bore, a screw thread and a plurality of radial slots intermediate said supporting surfaces, jaws mounted in said slots and having longitudinally-arranged, resilient members adapted to move in extensions of said slots, and an actuating hood having at its extremities supporting surfaces fitted to the concentric surfaces of the body and a screw-thread and conical surface intermediate its supporting surfaces.

5. A chuck having a body with slots therein, jaws in said slots, a hood adapted to operate said jaws and inclosing the same, and lugs projecting from said chuck body so as to be visible and located to serve as indices for the position of the jaws.

In testimony whereof, I hereunto affix my signature in the presence of two witnesses.

EUGENE C. PECK.
